(57) **CLAIM**

(21) **Appl. No.:** **29/713,669**

I claim the ornamental design for a regulator valve, as shown and described.

(22) **Filed:** **Nov. 18, 2019**

DESCRIPTION

(51) **LOC (13) Cl.** **23-01**

FIG. 1 is a perspective view of a regulator valve comprising a new, original and ornamental design;

(52) **U.S. Cl.**

FIG. 2 is a front elevational view of the regulator valve shown in FIG. 1;

USPC **D23/233**

FIG. 3 is a rear elevational view of the regulator valve shown in FIG. 1;

(58) **Field of Classification Search**

FIG. 4 is a left side view of the regulator valve shown in FIG. 1;

USPC D23/233, 235, 237, 241, 245, 247, 248;
137/198, 112, 315.04, 498, 14, 625.64,
137/625.23, 85; 251/330

FIG. 5 is a right side view of the regulator valve shown in FIG. 1;

CPC F16K 24/048; F16K 24/00; F16K 24/04;
F16K 24/06

FIG. 6 is a top plan view of the regulator valve shown in FIG. 1;

See application file for complete search history.

FIG. 7 is a bottom view of the regulator valve shown in FIG. 1; and,

(56) **References Cited**

FIG. 8 is another perspective view of the regulator valve of FIG. 1.

U.S. PATENT DOCUMENTS

The broken lines shown in the figures are for the purpose of illustrating portions of the regulator valve and form no part of the claimed design.
